CHARLES W. SCHULTZ, OF DETROIT, MICHIGAN; RICHARD E. SCHULTZ ADMINISTRATOR OF SAID CHARLES W. SCHULTZ, DECEASED.

CUSHION-SPRING.

1,146,026.

Specification of Letters Patent. Patented July 13, 1915.

Application filed March 13, 1912. Serial No. 683,448.

To all whom it may concern:

Be it known that I, CHARLES W. SCHULTZ, a citizen of the United States, and a resident of Detroit, in the county of Wayne and State of Michigan, have invented a new and useful Cushion-Spring, of which the following is a specification.

This invention relates to the construction of springs adapted for seats and seat-backs, and its object is to provide a cushion-spring which shall be soft and resilient, and wherein the free edges of the individual parts shall be prevented from moving independently of each other and in undesired directions.

This invention consists in combination with a frame, of helical springs mounted thereon in parallel rows, of transverse springs, comprising thin bands of resilient metal, connecting to the frame at one end and extending over the tops of the helical springs, a longitudinal strip of resilient metal connecting the free ends of the transverse springs, and means attached to said longitudinal band and to the frame for the purpose of controlling the movement of the ends of said transverse springs.

In the accompanying drawings Figure 1 is an elevation of a seat-back spring embodying this invention. Fig. 2 is an end elevation of the same. Fig. 3 is a similar elevation of a slightly modified construction. Fig. 4 is an end elevation of the top of another modified form of transverse spring. Fig. 5 is a plan of the strip which connects the free ends of the transverse springs.

Similar reference characters refer to like parts throughout the several views.

Automobile builders have been endeavoring to produce cushion springs for both seats and backs which shall give maximum comfort to passengers when the vehicle is traveling at high speed over rough roads. It has been found that the thick pad of curled hair, hitherto almost universally employed to upholster the seats and backs, was not entirely satisfactory, as it did not yield quickly when the passengers were subjected to jolts and jars because of the unevenness of the roadway over which the vehicle was passing. It was also found that by using a series of helical springs arranged in longitudinal rows, in combination with flat, resilient bands or springs extending over the tops of the same, a much better effect

was attained. In many cases it is desirable that the cushion-springs shall extend the entire height of the backs, in which case the cushion on the seat extends rearwardly against the cushion for the back. In some cases, however, this is not so desirable as to have the seat-cushion extend the full width of the seat and to have the back-cushion extend down only to the seat-cushion. The construction shown in the drawings is particularly adapted for this latter form of cushions. The resilient portion of this construction, when used for seat-backs, is mounted on a frame preferably composed of horizontal bars 1, 2, 3 and 4, which are connected by means of upright bars 5. Helical springs 6 are mounted on this frame and preferably connected immediately to the vertical bars 5, and arranged in parallel rows as shown in Fig. 1. Springs 7, in the form of thin strips of spring-metal, such as steel or brass, connect at one end to the upper bar 1 and then extend upward, forward and downward across the outer ends of the helical springs 6, connecting thereto in any desired manner. Extending along and connecting to the lower ends of these flat, transverse springs 7, is a thin, resilient cross-bar 8 having reentrant bends 9, as shown in Fig. 5, so that the movement of one spring 7 will be transmitted in part to the adjacent springs on each side. Whenever the pad 10, which extends over this cushion construction, is depressed at any one place, the lower ends of the springs 7 will yield and the bar 8 will bend. In order to prevent this bar from drawing the ends of the springs 7 laterally, the bar 8 is made expansible by means of the reentrant bends 9.

Referring to Fig. 2, it will be noticed that the weight of the pad 10 and of the springs, is liable to cause the helical springs 6 and the springs 7 to sag. In order to prevent this, the supporting members 12, which are formed from stiff spring-metal strips, connect to the outer ends of the bar 8, and after curving at the upper end, connect to the outer ends of the longitudinal bars 1 and 2. If desired, additional spring members 13 may be placed in the bend of the supporting member 12 to stiffen the same. As shown in Fig. 2, the seat-cushion 16 may be slipped underneath the lower edge of the spring construction just described.

When it is desired to embody this inven-

tion in a seat spring, no change need be made in the details, as all parts may be the same as those just described. If the drawing be turned to the right through an angle 5 of about eighty degrees, Fig. 2 will represent a seat-cushion construction, and the back cushion will be indicated in dotted lines by the part 15 and will extend down to the seat 17. Any desired means may be employed to secure the frame to the back 16, and the distance from the bar 8 to the seat 17 will depend upon the general construction and design of the vehicle.

Instead of the springs 7 shown in Fig. 2, 15 it may be desirable to use the flat strips 18, formed with reentrant bends 19, as shown in Fig. 3. This second construction is especially adapted for limousines where there is no possibility of the upper curved portions 20 of the springs 7 swinging back beyond the front line of the seat-back 16, as the seat-back 20 of the limousine usually extends upwardly beyond the top of the cushion. Where the transverse springs are formed 25 with reentrant bends as shown in Fig. 3, the upper portion will contract under pressure. Another method of forming these reentrant bends is shown in Fig. 4, where the flat springs 21 are formed with sharp bends 22. 30 These may be desirable where the construction shown in Fig. 3 might be objectionable, owing to the clicking sounds resulting from the edges 24, at the openings formed by the bends, contacting when unusual pressure is 35 exerted on the springs. To prevent the pad 10 from sagging down between the springs 7 or 18, small coil springs 26 may be employed to connect the upper bends of the transverse springs 7. In order to hold the springs 7 40 parallel to each other, clips 27 may be secured to them, between which clips the wires 28 may extend.

It will be understood that this invention is not limited in the number and size of the 45 helical springs 6, nor to the designs of the upper portions of the transverse springs 7, but resides in the lower portions of these springs, the connecting member 8, and the supporting members 12 therefor. The frame 50 formed by the bars 1 to 5 inclusive, may be omitted and the parts secured to the back 16 or any other desirable support.

I claim.

1. In a spring construction, the combination 55 of a supporting frame, a series of helical springs mounted thereon in longitudinal rows, a series of flat springs extending transversely across the tops of the helical 60 springs and curving to their points of connection with the upper edge of the frame, a

flat, resilient bar connecting to the free ends of said flat springs, and resilient supporting members connecting to the ends of said bar and to the upper part of said frame.

2. In a spring construction, the combination 65 of a supporting frame, a series of helical springs mounted thereon, substantially parallel flat springs secured to the upper part of the frame and extending forward and then downward across the outer ends of 70 the helical springs and connecting thereto, means connecting the flat springs between their connection with the frame and the upper helical springs, a resilient bar connecting the lower ends of the flat springs and 75 having reentrant portions between said flat springs, and strips of spring-metal connecting to the ends of said bar and extending upwardly, and having their upper portions bent substantially U-shaped and their ends secured 80 to the upper part of the frame so as to form a resilient support for said bar and springs.

3. In a spring construction, the combination 85 of a supporting frame, a series of helical springs mounted thereon, a series of upright springs secured to the upper part of the frame and forming arches to support upholstery and then extending downward across and beyond the outer ends of the helical springs and connected thereto, a rod 90 extending across the said construction below the helical springs and connected to said upright springs, and supporting members extending from said rod to the upper portion 95 of the supporting frame to prevent the upright springs from sagging an undesirable amount under the weight of the upholstery.

4. In a spring construction, the combination 100 of a rigid frame comprising horizontal and upright bars secured together, helical springs mounted on said frame, substantially flat springs secured to the upper part of the frame and forming arches to support upholstery and then extending downward 105 across the outer ends of the helical springs and connected thereto, a resilient bar connecting the lower ends of the flat springs, and a pair of supporting members extending from said bar to the rigid frame to prevent 110 the spring construction from sagging under the weight of the upholstery.

In testimony whereof I have signed this specification in the presence of two subscribing witnesses.

CHARLES W. SCHULTZ.
